NEW HAVEN, CONNECTICUT, A CORPORATION OF CONNECTICUT.

COLLAPSIBLE TAP.

No. 810,289.

Specification of Letters Patent.

Patented Jan. 16, 1906.

Application filed January 28, 1905. Serial No. 243,104.

To all whom it may concern:

Be it known that I, WILBUR A. LEONARD, a citizen of the United States of America, residing in the city of New Haven, county of 5 New Haven, State of Connecticut, have invented an Improved Collapsible Tap, of which the following is a specification.

The object of this invention is to produce a simple, easily-constructed, and readily-assembled automatic or collapsible tap, which will be thoroughly reliable in operation.

In the accompanying drawings, Figure 1 is a plan view, with portions broken away, of my improved tap with the cutters set to cutting position. Fig. 2 is a similar view of part of the tool with parts shown in the collapsed positions. Fig. 3 is a side elevation, with parts broken away and parts in section, of a tap in the position of Fig. 2. Fig. 4 is a 20 vertical longitudinal central section of a tap of slightly different proportions than that of the preceding figures. Fig. 5 is an end view with the cap or end plate removed. Fig. 6 is an end view. Fig. 7 is a side elevation of 25 the plunger. Fig. 8 is an end view of the plunger. Fig. 9 is a side view of one of the cutters, and Fig. 10 is an end view of the cutter.

My invention principally relates to the 30 plunger and cutter connections. The cutters 1, which are preferably tapering in breadth, Figs. 4 and 9, are each provided with the usual thread-cutting teeth 2 on their outer surface. On one of its side surfaces is 35 formed an oblique groove 10, preferably parallel to the inner edge of the cutter. These cutters fit into radial slots 3 near the end of the stock 5. The longitudinally-movable plunger 6 is formed with radial webs 7, each 40 projecting into a cutter-slot and provided with an oblique groove 8, forming a projecting rib 9, adapted to fit the groove 10 of the cutter. These oblique ribs and grooves form wedges in their action on the cutters. The 45 spindle 11 of the plunger enters a central hole 12 of the stock and is movable therein by a pin 13, fast in the spindle 11 and passing through a slot 14 in the mid-portion of the stock 5.

As the spindle 11 is moved longitudinally within the stock its grooves and projections engage the similar grooves and projections in the cutters and force them radially outward

or inward, as the direction of the motion is forward or backward.

I provide a spring 15, secured to a threaded adjustable rod 16* and to the end of the spindle 11, to tend to withdraw the plunger, and I provide a rotary cam-collar 16 on the stock to project the plunger and so set the cutters 60 to working position.

The cam-collar 16 can have a limited rotary motion upon the stock 5, and it has on its forward edge three surfaces, against which the cross-pin 13 of the plunger-spindle may 65 rest. One such surface 17 is a deep depression, allowing the pin to be drawn in by the spring 15 to entirely retract the cutters, while cam-faces 18 and 19, connected on opposite sides of surface 17, differ slightly from 70 each other in height, both being adapted to project the plunger and cutters to cut; but cam-face 19 projects them a little farther than does cam-face 18. Back of the cam-collar 16 is a ring 20, held in place by a threaded ring 21, screwed onto the stock. The collar 16 has a stud or handle 22, which is operated to throw the cross-pin 13 and its plunger onto any one of the three cam-faces 17, 18, 75 or 19, as may be desired.

To make the withdrawal of the cutters or collapsing of the tap automatic, I make the external sleeve 23 longitudinally movable on the stock to a limited extent, and this sleeve has an opening 23* in its shell with inclined 85 sides 24 25, through which the stud 22 projects, Figs. 1, 2, and 3. This sleeve is prevented from rotating relatively to the stock by pins 26 27 passing through slots 28 29 in the sleeve and secured on the stock.

An abutment-ring 30 of the usual type surrounds the stock and cutters and is secured to the casing 23 by means of side brackets 31, having slots 32, through which fastening-screws 33 pass to fasten them to 95 the casing.

In operation, the cutters being in the working position shown in Fig. 1, the stock 5 either rotates and enters the material to be tapped or the stock is held stationary and the 100 material to be threaded is rotated and one or other is fed forward. In either case the cutters enter and cut the thread to that depth determined by the height of the cam-face 18 (in the case illustrated) and to that length of 105 threaded surface determined by the position

- of the abutment-collar 30. When the collar 30 is struck by the material, the sleeve 23 is moved longitudinally backward on the stock, thereby causing the incline 24 to force the 5 stud 22 and cam-collar 16 toward the central position of Figs. 2, 3, and 4 and permitting the spring 15 to draw the spindle 11 and plunger 6 backward, with the plunger cross-pin 13 bearing against the cam-face 17.
- 10 As the plunger 6 moves backward it will draw the cutters radially inward from the work, which may be then slipped off the end of the stock or the tool withdrawn from the work.
- 15 If a finely-finished thread is desired, I may rotate the cam-collar by means of the handle-stud 22 to the opposite corner of the cam-opening 23* in the casing 23, adjacent to the incline 25, so as to cause the surface 19 to 20 move the plunger 6 and spindle 11, and consequently project the cutters farther out than before, whereupon the action first described may be repeated to cut a deeper and better-finished thread.
- 25 Although I have described my invention as embodied in a tap, it will be understood that some of the features may be embodied in screw-cutting dies.
- I claim as my invention—
- 30 1. A collapsible screw-thread-cutting implement, comprising a slotted stock, cutters in the slots, and a plunger longitudinally movable in the stock, with radial webs on the plunger projecting into the cutter-slots 35 with wedge-surfaces to act on the cutters.
2. A collapsible screw-thread-cutting implement, comprising a slotted stock, cutters in the slots, a plunger longitudinally movable in the stock, wedge-surfaces between 40 the plunger and cutters adapted to positively move the cutters upon the movement of the plunger, in combination with a pin in the plunger, a cam for said pin, an abutment-sleeve adapted for longitudinal movement
- on the stock, and means for operating the 45 cam by the movement of said abutment-sleeve.
3. A collapsible screw-thread-cutting implement, comprising a slotted stock, cutters in the slots, a plunger longitudinally mov- 50 able in the stock, wedge-surfaces between the plunger and cutters adapted to positively move the cutters upon the movement of the plunger, in combination with a cross- pin on the plunger, a cam-collar rotatable on 55 the stock having oppositely-inclined cam-faces of different heights and means for causing either of said faces to move the plunger- pin.
4. A collapsible screw-thread-cutting im- 60 plement, comprising a slotted stock, cutters in the slots, a plunger longitudinally mov- able in the stock, wedge-surfaces between the plunger and cutters adapted to positively move the cutters upon the movement 65 of the plunger, in combination with a cross- pin on the plunger, a cam-collar rotatable on the stock and engaged by said cross-pin, a back-stop for the collar, an operating- stud for the cam, an abutment-sleeve longi- 70 tudinally movable on the stock, and means for preventing its rotation thereon, a cam- groove in the casing through which the cam- stud projects and a return-spring for the plunger. 75
5. In combination, a stock having radial slots for the cutters and a plunger having radial webs projecting into said radial slots to there engage said cutters to move them inwardly, and outwardly by longitudinal movement of the plunger. 80
- In testimony whereof I have signed my name to this specification in the presence of two subscribing witnesses.
- WILBUR A. LEONARD.
